RACK FOR HOLDING TOILET ARTICLES, OR THE LIKE

Jennie L. Lopiano, 121 Olive Tree Ridge Road,
Noroton Heights, Darien, Conn.

Filed Dec. 29, 1965, Ser. No. 370

Term of patent 14 years

(Cl. D86—10)

FIG. 1 is a front perspective view of a rack for holding toilet articles, or the like showing my new design;

FIG. 2 is a side elevational view thereof.

The broken lines showing collapsible containers in FIG. 1 are for illustrative purposes only.

I claim:

The ornamental design for a rack for holding toilet articles, or the like, as shown and described.
